(57) **CLAIM**

The ornamental design for an apparatus for stimulation of the nervous system, as shown and described.

DESCRIPTION

FIG. 1 is a bottom isometric view of one embodiment of the design;

FIG. 2 is a top isometric view of the design shown in FIG. 1;

FIG. 3 is a top view of the design shown in FIG. 1;

FIG. 4 is left side view of the design shown in FIG. 1, and due to symmetry also a mirror image view of the right side of the design;

FIG. 5 is a front end view of the design shown in FIG. 1; and, FIG. 6 is a bottom view of the design shown in FIG. 1.
